SHIPPING AND DISPLAY CONTAINER

Michael P. Cortile, Chicago, Ill., assignor to
American Can Company, New York, N. Y., a
corporation of New Jersey

Application May 31, 1933, Serial No. 673,656

4 Claims. (Cl. 206—44)

The present invention relates to a combination shipping and display container for articles such as packaged goods that are displayed and sold, for example, in grocery stores or the like, and has particular reference to the maintenance of a stacked relation or display form for such articles which is provided before and maintained during shipment to the end that no rearrangement is necessary when the shipping case containing the same is opened by the grocer and the articles are taken out for display.

The present invention contemplates arranging the articles in attractive display form within a display holder which permits easy handling of the articles en masse for slipping into a shipping case and when the same are to be displayed, holder and articles are easily slipped out of the case and set up for display without disturbing their relationship.

Such a holder and shipping case is adapted to a combination unit for different sizes of articles such as packaged goods which are arranged in a display form and handled as before mentioned, a collection of different sizes being particularly desirable for small shipments which allow for a varied assortment of sizes in the one display group obviating the necessity of the small grocer, for example, stocking his store with a greater quantity of packages than he needs.

An object of the invention is the provision of a display unit of articles arranged in attractive display form within a holder which permits easy handling of the group without disarrangement of the individual articles and permits shipment in this form as well as subsequent display.

While such a display form may take any size or dimension desirable, depending upon the shape, size, or variety of shapes or sizes of the articles composing it, a pyramidal or step form is both attractive and desirable, that is, the outlines of the display group as a whole are not rectangular but the dimensions are of different lengths and/or breadths at different heights. Such a group mass when set into a rectangular shipping case is not closely confined and does not conform to the inside dimensions of the case, and the present invention under such circumstances contemplates the use of filler units to fill in such spaces and obtain the desired fit for shipment without disturbing the display form.

The invention also contemplates the use of a holder of simple construction which while supporting and holding the articles in their display form allows for a view of three sides of the display mass; also giving accessibility to the articles

to permit their individual removal from the stack if desired.

Numerous other objects and advantages of the invention will be apparent as it is better understood from the following description which, taken in connection with the accompanying drawing, discloses a preferred embodiment thereof.

Referring to the drawing:

Figure 1 is a perspective view of a shipping and display container embodying the present invention and illustrating the shipping case after filling and before it is closed;

Fig. 2 is a perspective view of the holder with the articles in display position and with the filler units in relation to the articles and as they would appear when removed from the shipping case;

Fig. 3 is a perspective view of the display holder and its contained articles, showing a preferred display form; and

Fig. 4 is a perspective view of the holder illustrating one side prior to being folded back into final holding position, parts being broken away.

The shipping case of the combination shipping and display container herein illustrated comprises a rectangular box 11 which may be formed from fibre stock in the usual manner, this box having upper flaps 12 adapted to be folded down into closed position in the usual way when the case is sealed for shipping.

A holder 13 is provided which may also be formed from fibrous material or other suitable stock, this holder having a rear vertical wall 14 (Fig. 4) and side walls 15 which preferably connect with a narrow front wall 16. The rear, side and front walls are bent at their lower ends to provide bottom flaps 17 which form the supporting bottom of the holder. Each side wall 15 is bent inwardly along a line of bend 18 (Fig. 4). The section of the side wall above the line of bend is brought down close against the inside of the holder 13, thus producing a triangular wall 21 (see also Fig. 3) of double thickness. Beyond the side fold and adjacent the rear wall 14 each side wall is again bent along a line of bend 22 (Fig. 4) and the flap against the rear wall 14 of each side 45 is hooked under and caught in a lug 23 struck-in from the rear wall by an arcuate cut 24.

The display holder so formed is adapted to support and maintain the articles in display position. In the drawing there is disclosed by way of example, an arrangement of three rows or tiers of different sizes of articles or packages, the larger size 25 resting upon the bottom 17 of the holder. The lower part of the holder, including the front wall 16, closely fits the lower row of articles. 55

An intermediate size of articles 26 is then superimposed upon the lower row of the larger size.

The smaller group in the second tier is set back from the front face of the larger articles below 5 and also from the side faces, as best illustrated in Fig. 3. Still another and smaller size of packages 27 is included in the display group herein considered and the outer faces of these are also set back from the front and side faces of the articles 10 below, thus producing a general pyramidal form of display. Along the back the three sized articles 25, 26, 27 engage the rear wall 14, which maintains them in vertical alignment and permits the attractive form of display illustrated in Fig. 3.

15 The triangular sides 21 of the side walls of the holder allow for a view of the display form and also permit accessibility to the individual articles in the display when removal of the articles is to be made.

20 Any other shape and size of display mass may be obtained by the proper combination of size and number of articles in the different rows. The outlines of the display mass will, however, for the most part, be other than rectangular and a cubical mass will ordinarily not be used.

25 The bottom 17 of the holder 13 is slightly smaller than the bottom of the case 11 and the holder with its stacked articles may be easily inserted in the case 11. In order to fill in the spaces 30 between the inside walls of the case and the outside walls of the articles in the different rows filler units are used. To this end the spaces within the holder 13 adjacent the intermediate row are preferably filled with side filler units 31 and 35 a front filler unit 32.

30 These filler units may be formed in any suitable manner, a skeleton form preferably of fibrous material as disclosed in the drawing being found satisfactory for the purpose. The spaces adjacent 40 the upper row of articles 27 are also filled with side filler units 33 and a front filler unit 34. The lower row may fit the surrounding walls of the holder and no filler units need be used.

45 These filler units may be inserted in the holder 13 and a rectangular mass of filler units and articles may be obtained prior to the insertion of the holder 13 into the shipping case 11 or the holder with the articles may be first inserted and the filler units afterwards placed separately in 50 the shipping case. The first method is illustrated in Fig. 2, the holder 13 being completely filled with its articles in display position and with the filler units arranged around in their proper positions adjacent and on the articles so that the 55 entire rectangular or substantially cubical outline of the combination is a unit mass as shown.

60 In either event, by using the filler units the display form of the articles is maintained in position within the holder 13. By means of the 65 holder the articles en masse are easily slipped into the shipping case 11 when shipment is made. The articles, the filler units and the holder are also easily taken out of the case, the latter affording an easy carrier or support. It is then only necessary to take off the filler units in order to fit the combination holder and unit mass for display, as shown in Fig. 3.

70 It is thought that the invention and many of its attendant advantages will be understood from the foregoing description, and it will be apparent that various changes may be made in the form, construction and arrangement of the parts without departing from the spirit and scope of the 75 invention or sacrificing all of its material advan-

tages, the form hereinbefore described being merely a preferred embodiment thereof.

I claim:

1. A combination shipping and display container, comprising a display holder adapted to retain a plurality of different sizes of articles in shipping and display positions, said holder having a horizontal bottom which is shaped to support one tier of articles of a given size and having surrounding walls which snugly hold these articles in a predetermined arrangement, the rear wall of said holder aligning the back edges of the articles in the lower tier with the back edges of the smaller articles in other superimposed tiers, each side wall of said holder being folded upon itself to constitute rearwardly inclined reinforced walls of double thickness permitting clear visibility of the superposed tiers of articles carried by the display holder, said arrangement constituting a combination display and shipping position for the articles, all of the articles in each tier being of the same given size which is larger than those in the next tier directly above, and a shipping case for enclosing said holder and its positioned articles while retaining their arrangement, said display holder with its individual articles providing an article display unit which may be easily withdrawn from the shipping case when used in its display capacity.

2. A combination shipping and display container, comprising a display holder adapted to retain a plurality of different sizes of articles in shipping and display positions, said holder having a horizontal bottom which is shaped to support one tier of articles of a given size and having surrounding walls which snugly hold these articles in a predetermined arrangement, the rear wall of said holder aligning the back edges of the articles in the lower tier with the back edges of the smaller articles in other superimposed tiers, each side wall of said holder being folded upon itself to constitute rearwardly inclined reinforced walls of double thickness permitting clear visibility of the superposed tiers of articles carried by the display holder, said arrangement constituting a combination display and shipping position for the articles, all of the articles in each tier being of the same given size which is larger than those in the next tier directly above, a shipping case for enclosing said holder and its positioned articles while retaining their arrangement, said display holder with its individual articles providing an article display unit which may be easily withdrawn from the shipping case when used in its display capacity, and skeleton filler units for filling the side and front spaces occasioned by the receding arrangement of the superimposed tiers of different sizes of articles to provide a snug fit in the said shipping case, said skeleton filler units being removed when the article display unit is withdrawn from said shipping case.

3. A combination shipping and display container, comprising a display holder adapted to retain a plurality of different sizes of articles in shipping and display positions, said holder having a horizontal bottom which is shaped to support one tier of articles of a given size and having surrounding walls which snugly hold these articles in a predetermined arrangement, the rear wall of said holder aligning the back edges of the articles in the lower tier with the back edges of the smaller articles in other superimposed tiers, each side wall of said holder being folded upon

itself to constitute rearwardly inclined reenforced walls of double thickness permitting clear visibility of the superposed tiers of articles carried by the display holder, the folded portion of each side wall being again folded to extend partially across the said rear wall and secured thereto to augment the reenforcement of the display holder, said arrangement constituting a combination display and shipping position for the articles, all of the articles in each tier being of the same given size which is larger than those in the next tier directly above, and a shipping case for enclosing said holder and its positioned articles while retaining their arrangement, said display holder with its individual articles providing an article display unit which may be easily withdrawn from the shipping case when used in its display capacity.

4. A combination shipping and display container, comprising a display holder adapted to retain a plurality of different sizes of articles in shipping and display positions, said holder having a horizontal bottom which is shaped to support one tier of articles of a given size and having surrounding walls which snugly hold these articles in a predetermined arrangement, the rear wall of said holder aligning the back edges of the articles in the lower tier with the back edges

of the smaller articles in other superimposed tiers, each side wall of said holder being folded upon itself to constitute rearwardly inclined reenforced walls of double thickness permitting clear visibility of the superposed tiers of articles carried by the display holder, the folded portion of each side wall being again folded to extend partially across the said rear wall and secured thereto to augment the reenforcement of the display holder, said arrangement constituting a combination display and shipping position for the articles, all of the articles in each tier being of the same given size which is larger than those in the next tier directly above, a shipping case for enclosing said holder, and its positioned articles while retaining their arrangement, said display holder with its individual articles providing an article display unit which may be easily withdrawn from the shipping case when used in its display capacity, and skeleton filler units for filling the side and front spaces occasioned by the receding arrangement of the superimposed tiers of different sizes of articles to provide a snug fit in the said shipping case, said skeleton filler units being removed when the article display unit is withdrawn from said shipping case.
